METHOD FOR THE MANUFACTURE OF
PROPIONIC ALDEHYDE

Milton Gallagher and Rudolph Leonard Hasche,
Kingsport, Tenn., assignors, by mesne assignments,
to Eastman Kodak Company, Jersey
City, N. J., a corporation of New Jersey

Application July 3, 1936, Serial No. 88,822

9 Claims. (Cl. 260—601)

This invention relates to the manufacture of saturated aliphatic aldehydes and acids and, more particularly, to a process for the manufacture of propionic aldehyde and propionic acid.

Propionic aldehyde, also referred to as propanal, with which this invention is particularly concerned, has the formula: $\text{CH}_3\text{CH}_2\text{CHO}$. Saturated aliphatic aldehydes and acids and, in particular, propionic aldehyde and acid have a number of uses. These organic compounds may be converted to other chemical products. For example, propionic acid is employed in the manufacture of cellulose esters. Propionic aldehyde may serve as a material for the production of propionic acid and employ the oxidation procedure described in Hasche copending application No. 34,215 of August 1, 1935.

While some saturated aliphatic aldehydes containing an even number of carbon atoms and their methods of preparation are known, apparently few methods have been developed for the manufacture of the saturated aldehydes and acids containing an odd number of carbon atoms, such as propionic aldehyde and acid with which the present invention is particularly concerned.

Prior to our invention the manufacture of propionic aldehyde has been confined in a number of instances to the dehydrogenation of alcohol or processes involving pressure synthesis.

We have found a new method for the manufacture of saturated aliphatic aldehydes and, in particular, for the manufacture of aldehydes containing an odd number of carbon atoms in the molecule, which is superior in a number of respects to processes previously employed in the manufacture of saturated aliphatic aldehydes.

This invention has for an object to provide a process for combining two different aldehydes in the vapor phase to form an aldehyde which may contain either an odd or an even number of carbon atoms. Another object is to provide a process for the production of saturated aliphatic aldehydes containing an odd number of carbon atoms in the molecule. Still another object is to provide a vapor and liquid phase catalytic process for the production of saturated aliphatic aldehydes. Another object is to provide a simple and efficient process for the production of saturated aliphatic aldehydes which operate on readily produced or available raw materials. Still another object is to provide a catalytic process for the reaction of a plurality of aliphatic aldehydes containing a different number of carbon atoms in the molecule and the subsequent conversion of the reaction products to saturated aldehydes. A still

further object is to provide a process particularly adapted for the production of the saturated aliphatic aldehyde, propionic aldehyde. Another object is to provide a catalytic process for the production of acrolein and the conversion of this product to propionic aldehyde. As another object we provide for the formation of a three-carbon atom from formaldehyde and acetaldehyde which may later be converted into propionic acid by oxidation. Another object is to provide a process wherein unreacted products may be re-utilized as starting materials. A further object is to provide a process which operates without pressure, but may include the use of pressure if desired.

Still another object is to provide catalysts and catalyst supports for a process involving the reaction of aldehydes containing a different number of carbon atoms in the molecule to obtain saturated aldehydes. Another object is to provide catalysts and catalyst supports for the reaction of materials containing formaldehyde with materials containing acetaldehyde to obtain saturated aldehydes, by reduction of the resultant reaction products.

Still another object is to provide apparatus which is simple and inexpensive yet suitable for the reaction of various aliphatic aldehydes to obtain unsaturated aliphatic aldehydes therefrom coupled with the conversion thereof to saturated aldehydes and acids.

Other objects will appear hereinafter.

These objects are accomplished by the following invention which includes the steps of catalytically reacting at least two aliphatic aldehydes having a different number of carbon atoms in the molecule followed by reduction of the reaction mixture. In accordance with our preferred procedure, we have found that excellent yields of propionic aldehyde may be obtained by catalytically reacting formaldehyde and acetaldehyde followed by reduction of the reaction products.

For further details concerning our new process and apparatus and a more complete understanding of our invention, reference is made to the accompanying drawing which forms a part of the present application. In the accompanying drawing, in which like reference characters refer to like parts,

Fig. 1 is a diagrammatic side elevation showing an apparatus set up for practicing our new process.

Fig. 2 is a semi-diagrammatic side elevation of a larger apparatus for carrying our new process

on a larger scale. In both figures certain parts of the apparatus have been shown on section or in exaggerated scale for clarity.

Fig. 1 discloses a catalytic unit for carrying out 5 our process. The unit of Fig. 1 is quite similar to the unit described under Fig. 2. A feed tank 11 is provided for one of the components. This tank is connected by conduit 12 to the mixing point 15. Another feeding device 16 is provided 10 for another component. Conduit 14 connects this device with the mixing point. The conduit 13 leads from the mixing point to the vaporizer 17. Or, in place of the two tanks, 11 and 16, the 15 two different aldehydes may be premixed in the desired proportions in a single tank and fed to the vaporizing or flashing device.

The apparatus 17 may be of well-known construction and include heating elements, spraying means or other elements for converting liquids 20 to vapors. Vaporizer 17 is connected by conduit 18 to catalyst unit 19.

Catalyst unit 19 may be maintained at the proper temperature by means of a coil 21. The outside of the unit is insulated as at 22. Also, 25 if desired, the conduits 18 and 24 may be heated. The catalyst unit includes a charge of catalyst 23. Conduit 24 is provided for withdrawing the reaction products to a catalyst or other treatment. The catalyst units are equipped with thermometer wells 25 and 35 whereby the temperature in 30 the interior of the units may be measured by insertion of a thermocouple or thermometer.

Conduits 24 and 27 connect catalyst unit 19 with a second unit 28 of similar construction. 35 Unit 28 comprises heating elements 29, reaction chamber 31. In place of this unit any well-known hydrogenation unit may be employed.

A conduit 32, joining conduit 24-27, or leading 40 directly into unit 28 is provided for the introduction of a hydrogenating medium. Conduit 33 which leads through condenser 36 is provided for 45 withdrawing the reaction products. It is understood that the various feed tanks, feed lines and the like will be equipped with vent condensers, pop valves and the like.

In Fig. 2, 52 represents a feed tank for one of 50 the starting materials. The tank is connected by conduit 53 through a meter 54 or other suitable device to vaporizer 56. Vaporizer 56 is connected by conduit 57 to mixing valve or chamber 58.

In a similar manner another feed tank 62 is provided for the other starting material. Tank 62 is connected by conduit 61 through a rotameter 65 to a vaporizer or boiler 63. Conduit 64 connects boiler 63 with mixing chamber 58. 55 The feed tanks, feed heaters, boiler or vaporizers in the system will include jackets or other temperature controlling means as at 66, 67 or 68 for the purpose of regulating the temperature of the respective containers. In the apparatus 60 shown in Fig. 2 this would be done by injection of heating or cooling fluids in the jackets as the situation required.

The mixing valve or mixing chamber 58 may 65 be connected by conduit 69 through heat exchanger 71 to a catalyst chamber 72. This heat exchanger is provided with a valved by-pass 92. The catalyst chamber comprises a catalyst container filled with catalyst. This catalyst may be 70 retained by screens or other means as at 73 and 74. The catalyst is enclosed in temperature controlling jackets 70, 76. The jacket 76 may be heated by steam, hot oil, molten chemicals, electric heat or in some other suitable manner, or 75 cooling fluid may be injected if necessary. The

chamber 70 is provided so that the incoming mixture may be passed in heat exchange relationship with the catalyst to absorb heat or reaction therefrom.

While we have described the above type catalyst chamber other types of catalysts may be employed, such as for example the various other catalyst units shown in Hasche copending application No. 34,215. Also in the present set-up it is possible to use the vaporizers and other type equipment shown in Hasche application No. 34,215.

Catalyzer 71 is joined to condenser 77 by conduit 75. This condenser may be of the usual construction. A valved conduit 78 is provided in 15 order that the condensate may be withdrawn from the condenser to tank 79. Means for the separation of unreacted aldehydes and return to feed may be inserted in system, as in line 78 for example.

Tank 79 is arranged so that its contents may be caused to flow through conduit 81 by pumping or gravity feed, to a reduction unit 82. The reduction unit may comprise any standard hydrogenation unit.

Leading into the catalyst chamber, or into conduit 81 is a valved conduit 87 through which the reducing medium, such as hydrogen or material yielding nascent hydrogen may be introduced.

The catalyst (or hydrogenation chamber) is provided with conduit 88 which leads to condenser 89. Condenser 89 is equipped with a valved draw-off conduit 91.

Catalyst chambers 23 and 72 are filled with 35 catalyst. A number of catalysts have been found to be satisfactory for the reaction of an aliphatic aldehyde with a different aliphatic aldehyde. Silica or alumina gel alone appear to be 40 satisfactory catalysts. However, the action of these gels may be improved by impregnating them or incorporating therewith additional materials, such as sodium acetate, magnesium acetate, cadmium acetate, thoria, molybdenum oxide or cobalt metal. When we refer to "gel catalyst" we refer to catalysts such as described 45 above. While the above catalysts are satisfactory, our invention is not limited to these catalysts or catalyst supports. For example, a suitable catalyst for carrying out our aldehyde reaction is magnesia supporting about 2-10% of metallic cobalt. Or magnesia formate, vanadium pent oxide or tungstic oxide, on a gel carrier 50 may be employed. Or magnesium oxide made into granular form is satisfactory. The temperature conditions under which any particular catalyst will operate in our process may vary somewhat. Temperatures between about 200-400° C. 55 appear to be satisfactory, and within this range the range of about 290° C. to 300° C. appears 60 preferable in many instances.

The operation of our new process and apparatus may be better understood by reference to the following examples which are set forth merely for the purpose of illustration. The following example is described as carried out in the apparatus of Fig. 1.

The container 11 was filled with a relatively pure liquid acetaldehyde. Container 16 was filled with formalin. A metered amount of acetaldehyde was mixed with formalin at 15. This mixture was conducted through conduit 13 into flash apparatus 17.

The mixture of acetaldehyde and formaldehyde were readily vaporized in 17 and the mix- 65

ture of vapors conducted through conduit 18 to catalyst unit 19. The catalyst unit had been heated and during the reaction was maintained in a heated condition by means of an electrical heating coil 21.

During the run of this example approximately 101.3 grams of acetaldehyde and approximately 84 grams of formalin containing approximately 35% formaldehyde by weight were fed to the catalyst unit. The catalyst chamber, which was filled with one of the aforementioned catalysts, was held at about 285° C. by electrical heating. The acrolein containing materials produced were conducted through conduit 24-27 to the hydrogenation apparatus 28, wherein hydrogenation was carried out consuming approximately 14.42 grams of hydrogen supplied through 32.

Unit 28 may be filled with any known hydrogenation catalyst such as copper, nickel, platinum, etc. However, in the hydrogenation step it is desirable to avoid the use of a catalyst which is too active and which would carry reduction too far thereby resulting in the production of excessive quantities of propyl alcohol. One satisfactory catalyst is nickel resulting from an alloy of nickel with aluminum, silicon or the like. These other components are removed from the nickel before its use as a catalyst. In this particular run the temperature was held at about 195° C.

The reaction products were conducted from unit 28 through conduit 33 and condenser 36 and into a fractionating column (not shown). The condensed product on fractionation consisted approximately of 47.1 grams of acetic aldehyde, 51.8 grams of propionic aldehyde, 13.3 grams of ethyl alcohol, certain amounts of unreacted formic aldehyde, and methanol. The exit gases contained approximately 85.0% H₂. This yield of the saturated aldehyde, propionic aldehyde, indicates that a satisfactory yield of the unsaturated aldehyde, acrolein was obtained in the preceding step.

The following example is described with respect to Fig. 2. Tank 52 was filled with commercial acetaldehyde. Inasmuch as acetaldehyde has a boiling point of about 21° C. it may be desirable to circulate a cooling medium in jacket 66 to prevent volatilization of the aldehyde. In place of the cooling jacket it is, of course, apparent that cooling coils may be immersed in the acetaldehyde. The acetaldehyde was fed through rotameter 54 into vaporizer 56. Acetaldehyde vapors from 56 were conducted to mixing chamber 58.

In our process it is possible to use acetaldehyde from various sources. For example, the acetaldehyde may be obtained synthetically from acetylene. The acetylene may be produced from calcium carbide, cracking hydrocarbons or the decomposition of hydrocarbons in an electric arc. The acetaldehyde may also be obtained from ethyl alcohol. The use of aldehyde from this source will be described in more detail herein-after.

Formaldehyde (or materials containing formaldehyde) was placed in container 62. This container may be heated or cooled or otherwise acted upon dependent upon the particular formaldehyde material.

Relatively pure formaldehyde boils at approximately -21° C. Formalin, which contains around 40% of formaldehyde, the remainder being principally methyl alcohol and water has a higher boiling point and is an easier source of

formaldehyde to work with. Also formalin is readily available commercially. We have found that the methyl alcohol content of formalin or of other sources of formaldehyde does not interfere with our process. Solid paraformaldehyde 5 may be employed. It is, therefore, apparent that our invention embraces various sources of formaldehyde. We also contemplate the added steps of converting methyl alcohol into formaldehyde and feeding the resultant reaction mixture 10 through conduits 61 and 64.

In the example under description the formaldehyde materials were fed through rotameter 65 into the formaldehyde boiler 63. The evolved vapors containing formaldehyde were conducted 15 through conduit 64 to the mixing point 58.

From 58 the vapors containing formaldehyde and acetaldehyde, with or without water, methyl alcohol and other non-detrimental components, were passed into and through catalyst 72. This 20 catalyst which comprised either silica or alumina gel, was heated to approximately 290° C. to 300° C. After a period of operation, which may be from 12 to 24 hours, the catalyst may be regenerated.

The following reaction apparently took place:

The vapors from the catalyst chamber coming off at 75 were passed through cooling device 77. 35 At 78 acrolein containing some water, unreacted formaldehyde and acetaldehyde was withdrawn to tank 79.

The reaction of two different aliphatic aldehydes, such as formaldehyde with acetaldehyde, 40 per se, is described and claimed in our co-pending application Serial No. 88,821 entitled "Process for the manufacture of unsaturated aldehydes and apparatus therefor."

The condensed materials of acrolein, formalin, 45 acetaldehyde and water may be vaporized and conducted from tank 79 into hydrogenation unit 82. Or, the materials in the uncondensed condition, as at 75, may be passed directly to the hydrogenator in a manner similar to that of Fig. 1. 50 As indicated above, any well-known hydrogenation catalyst such as nickel, copper and the like, either in the form of a supported catalyst, or in solution, or in a vaporous state may be employed in the hydrogenator 82. We have found 55 that treating the acrolein in admixture with other components possesses a number of advantages. The cost and trouble of isolating acrolein as such is eliminated by treating the reaction mixture directly. Losses of acrolein by polymerization are 60 reduced. The other products present are not converted into useless or detrimental materials.

A source of hydrogen suitable for hydrogenation was supplied through conduit 87. In accordance with the example under description, the materials were charged into the hydrogenation apparatus. A temperature of between 50-400° C. was maintained in the hydrogenator.

Our hydrogenation proceeds selectively to reduce the double bond of the acrolein yielding 70 propionaldehyde. Apparently the hydrogen does not attack the aldehyde group. The acetaldehyde and formaldehyde present with the acrolein are not appreciably attacked during the reaction. This is observed by measurement of the absorp- 75

tion of hydrogen. The reaction which probably takes place is as follows:

10 The liquid in the hydrogenator at the end of the reaction was subjected to fractional distillation. The acetaldehyde, boiling at approximately 20° C., was first distilled off. The next fraction boiling at about 47° C. contains propionic aldehyde. This fraction containing the propionic aldehyde may be fed through any of the oxidation units shown and described in Hasche pending application Serial No. 34,125. By such treatment the propionic aldehyde may be catalytically oxidized to propionic acid.

20 The above examples are merely illustrative of conditions for carrying out our process. Reaction conditions in the various steps may be altered and the above examples are not to be construed as limiting our invention.

26 as limiting our invention.
For example, the mol ratio of acetaldehyde to
formaldehyde while generally kept within the
range of from 5-5, may be varied outside of
these limits. Generally we employ excess of the
30 acetaldehyde and otherwise operate the process
to consume the most, if not all of the formalde-
hyde in one pass. The reaction products col-
lected in 79 would consequently show excess acet-
aldehyde but smaller formaldehyde. The subse-
35 quent hydrogenation step may convert some of
the acetaldehyde into ethyl alcohol. However,
the ethyl alcohol may be separated or converted
to acetaldehyde by any of a number of known
processes and the acetaldehyde returned to the
first step of our process along with unreacted
40 acetaldehyde.

Any formaldehyde which becomes hydrogenated into methanol may be reconverted and refluxed through the system.

The space velocities employed in the formation of the unsaturated aldehyde which is subsequent-
ly hydrogenated may vary according to conditions and reaction equipment. We have found the range, from approximately 200 to 3000, to be suitable for carrying out the reaction of two different aliphatic aldehydes. We may define "space velocity" as cubic feet of reactants fed per cubic foot catalyst per hour—volumes of reactant materials measured at temperatures and pressures of reaction. As already indicated the temperature range for reacting formaldehyde with acetaldehyde may vary from about 200° C. to 400° C. While we prefer to carry out the formaldehyde-acetaldehyde reaction under atmospheric conditions it is possible to carry out the reaction under either higher or lower pressures.

With respect to the hydrogenation step, this reaction may be carried out at temperatures in excess of 200-300° C. and in the vapor phase. Various pressures varying from about substantially no pressure up to 300 or 400 pounds are satisfactory, although no pressure or the lower pressures within this range are preferred, because of simplicity of operation and construction of equipment.

70 Our novel procedure described herein represents a particularly satisfactory method for the manufacture of saturated aliphatic aldehydes. Our preferred embodiment for the manufacture of aliphatic aldehydes containing an odd number
75 of carbon atoms such as propionic aldehyde, per-

mits the utilization of materials, such as formalin, acetaldehyde and hydrogen. Our process is also particularly desirable from the standpoint that any by-products produced are few in number and in relatively small quantities, when our process is properly employed. The by-products may be re-used. Any unreacted components may be re-utilized by circulation through the system.

It will be understood that our apparatus will be constructed of suitable materials and that proper precautions for preventing heat losses and leakage will be observed. We find that many of the parts of our apparatus may be constructed of a steel containing about 16-23% chromium, about 7%-20% nickel and the balance substantially iron. This steel preferably has a content of carbon of about .10% or less. The steel may also contain small amounts of copper, silicon, molybdenum and tungsten. 10 15

The term "rotameter" as employed herein refers to liquid measuring devices. 20

It is, therefore, apparent that while we have described our invention in some detail there are many changes that may be made therein without departing from the spirit of the invention. 25

What we claim and desire to secure by Letters Patent of the United States is:

1. A process for the production of a saturated aliphatic aldehyde, which comprises reacting two different aliphatic aldehydes, each having a lesser number of carbon atoms in the molecule than the aldehyde to be produced, in the presence of a catalyst, maintaining conditions at least part of the time whereby the reaction will take place in the vapor phase to yield a reaction mixture containing an unsaturated aldehyde, at least one saturated aldehyde and water, continuously subjecting this reaction mixture in the vapor phase to a treatment which causes hydrogenation of substantially only the unsaturated aldehyde to the desired aldehyde, and separating the desired aldehyde from the reaction mixture. 40

2. A process for the production of saturated aliphatic aldehydes which comprises reacting materials containing formaldehyde and at least one other aliphatic aldehyde in the vapor phase with space velocity within the range of from 200 to 3000, in contact with a catalyst maintained at a temperature between about 200° C. and 400° C. to yield a reaction mixture containing an unsaturated aldehyde, at least one saturated aldehyde and water, and subjecting at least a part of this reaction mixture while in the vapor phase to a treatment which causes hydrogenation of substantially only the unsaturated aldehyde, thereby producing the desired saturated aldehyde. 55

3. A process for producing saturated aliphatic aldehydes, which comprises passing materials containing at least two different aliphatic aldehydes in the vapor phase at space velocities between 300 to 2000 into contact with a gel catalyst maintained at a temperature between about 200° C. and 400° C., condensing the reaction products to yield a reaction mixture containing an unsaturated aldehyde, at least one saturated aldehyde and water, substantially immediately subjecting this reaction mixture in the vapor phase to a treatment at a temperature between 50° C.-400° C. in the presence of a hydrogenation catalyst and medium to cause hydrogenation of the unsaturated aldehyde to a saturated aldehyde, and separating this saturated aldehyde from the reaction mixture by distillation

4. A process for the production of propionic aldehyde, which comprises reacting formalin with 75

- acetaldehyde in the presence of a gel catalyst containing a metal acetate, the reaction being maintained under conditions of temperature and pressure which cause the formation of reaction products containing acrolein, a saturated aldehyde and water, subjecting at least a part of this reaction mixture to catalytic hydrogenation at a temperature between 50° C.-400° C. in the presence of hydrogenation medium so that the acrolein is hydrogenated to propionic aldehyde but the other components of the reaction mixture are not substantially hydrogenated.
5. The chemical process which comprises reacting formaldehyde and acetaldehyde in the vapor phase and in the presence of a gel catalyst maintained at a temperature between about 150° C. and 400° C. to produce reaction products containing acrolein, acetaldehyde, formaldehyde and water, condensing the reaction products produced, and subjecting at least a part of the reaction materials to catalytic hydrogenation under conditions sufficiently vigorous to cause the hydrogenation of acrolein but insufficient to cause substantial hydrogenation of other materials in the reaction mixture.
6. The chemical process for the production of a straight chain aliphatic aldehyde, which comprises preparing a reaction mixture containing the corresponding unsaturated aldehyde by the reaction in the vapor phase of other aldehydes, and then substantially immediately subjecting the reaction mixture in the vapor phase to a hydrogenation treatment wherein unsaturated aliphatic aldehyde is converted to said straight chain aldehyde, and separating the straight chain aldehyde from the reaction mixture.
7. A process for the production of aliphatic aldehyde compounds, which comprises vaporizing an aliphatic aldehyde containing a lesser number of carbon atoms than the aldehyde being produced,
- vaporizing another aldehyde different from the aforementioned aldehydes, mixing the aldehyde vapors, contacting the vaporous mixture with a catalyst maintained at a temperature between 150° C. and 400° C. to cause reaction between the aldehydes and the production of a reaction mixture containing an unsaturated aldehyde, at least one saturated aldehyde and water, subjecting this reaction mixture to a hydrogenation treatment sufficiently vigorous to cause the hydrogenation of the unsaturated aldehyde to the desired saturated aldehyde but insufficient to cause material hydrogenation of other components of the reaction mixture, and separating the desired aldehyde from the reaction mixture.
8. The chemical process which comprises vaporizing an aliphatic aldehyde containing less than four carbon atoms, vaporizing another and different aliphatic aldehyde, reacting at least a part of the resulting aldehyde vapors in the presence of a gel containing catalyst maintained under temperature and pressure conditions which will cause reaction between the vaporized aldehydes, cooling the reaction products, and subjecting the reaction products to treatment with free hydrogen, in the presence of a hydrogenation catalyst.
9. A process for the manufacture of propionic aldehyde, which comprises vaporizing materials containing acetaldehyde, vaporizing materials containing formaldehyde, reacting together at least a part of the vaporized materials in the presence of a catalyst maintained at a temperature between about 200° C. and 400° C., subjecting the reaction products from the aforementioned treatment to condensation and then to hydrogenation in the presence of a nickel hydrogenation catalyst derived from an alloy of nickel.

MILTON GALLAGHER.

RUDOLPH LEONARD HASCHE. 40
